UNITED STATES PATENT OFFICE.

THOMAS J. BARRON, OF NEWNAN, GEORGIA.

LEVELING-INSTRUMENT.

SPECIFICATION forming part of Letters Patent No. 331,604, dated December 1, 1885.

Application filed May 4, 1885. Serial No. 164,343. (No model.)

To all whom it may concern:

Be it known that I, THOMAS J. BARRON, of Newnan, in the State of Georgia, have invented certain new and useful Improvements 5 in Leveling-Instruments; and I do hereby declare the following to be a full, clear, and exact description of the invention, such as will enable others skilled in the art to which it pertains to make and use it, reference being 10 had to the accompanying drawings, which form part of this specification.

My invention relates to an improvement in leveling-instruments; and it consists in, first, the combination of the tripod, the staff which 15 is vertically adjustable thereon, and which is provided at its upper end with a ball-bearing, with the table or bearing which is applied thereto, and which has a socket in its under side to receive the ball and revolve freely 20 thereon; second, the combination of the tripod, the staff, the table or frame which is journaled upon its top, and which has a socket in its under side to receive the ball-bearing of the staff, and a socket on its upper side in 25 which the sighting-tube and level are placed and loosely held in such a manner that they can be revolved freely around; third, the combination of the tripod, the staff, the table or frame carrying the sighting-tube upon its top, 30 the vertical rods or braces, the circular frame, which is secured to their lower ends, and which serves as a counter-balance, and a bridge which extends across the top of the frame, and through which the set-screws are passed for 35 the purpose of adjusting the table or frame upon the top of the staff, all of which will be more fully described hereinafter.

Figure 1 represents a side elevation of a leveling-instrument embodying my invention, 40 partly in sections. Fig. 2 is a horizontal section of the same, looking down upon the balancing-frame. Fig. 3 shows another form or frame or sighting devices. Fig. 4 is a plan view of the table alone. Fig. 5 is a vertical 45 cross-section taken through the table alone and at right angles to Fig. 1.

A represents the tripod, which may either be of the construction here shown or any other that may be preferred. Passing through 50 the socket upon the top of this tripod is the staff B, which is held in any desired relation

by means of the set-screw C, which passes through the side of the socket and bears against the side of the rod. This rod B is preferably made hollow for the sake of lightness, and secured in its upper end by means of the clamping-screw E is a vertical adjustable rod, F, which has a ball-bearing, G, formed upon its upper end. This rod F is made vertically adjustable upon the staff for 55 the purpose of raising and lowering the frame or table which carries the sighting-tube, without the necessity of making the adjustment upon the top of the tripod. By having a bearing, G, as shown, the frame carrying the 60 sighting-tube upon its top readily adjusts itself to a level as soon as it is left free to move.

The table or frame H is preferably made round, and has ears or projections I formed on opposite sides, as shown. In the under 70 side of this table or frame is formed a socket, J, in which the bearing G fits. In the top of the table or frame is made a large circular socket, in which the bearing or pivot R' for the sighting-tube and level is placed. Extending 75 through the ears or projections formed upon opposite sides of the table or frame are the vertical rods L, which have their lower ends passed through the circular frame and counter-weight N. The holes or openings which 80 are made through this frame N are made larger than are necessary simply to allow the ends of the rods to pass through, and one of them is made in the form of a slot, so as to allow the frame to be adjusted upon the rods in case one 85 side should happen to be heavier than the other. By means of this adjustment the frame can be attached to the rods so that it will always swing freely to a center and exactly balance the frame or table and the sighting-tube 90 placed thereon. Were it not for this adjustment, when this frame was left free to vibrate, it would not bring the bubble to the center of the level if the frame were heavier on one side than on the other. Extending across the top 95 of this circular frame or counter-balance N is the bridge O, which is arched at its center, so as to raise it slightly upward, and which has an opening through each end, so as to allow the vertical rods to pass through and center it 100 in position between the rods of the frame. At the center of this bridge is formed a ring or

collar, Q, through which are passed the four set-screws R. These screws, by bearing against the side of the staff, adjust the frame or table into any desired position. When the instrument is first set up, these set-screws are slackened, and then the counter-weight N causes the table to at once adjust itself into a horizontal position. As soon as the bubble of the level shows that the table is in a horizontal position the screws are tightened against the staff, so as to hold it rigidly in place.

The bearing or pivot R' of the frame upon which the sighting-tube and level are placed is made circular, so as to fit in the circular socket in the top of the table, and is grooved upon its edge, so that the set-screws which pass through the side of the table will catch in the groove, and, while they prevent the pivot or bearing from being removed from its socket, allow it to revolve freely around therein, so as to move the sighting-tube in any direction. The level may be placed just over the pivot, as shown, where a sighting-tube is used; or, if simply sights are used instead of a tube, it may be placed upon the top of the frame. The bridge is here shown above the top of the frame N; but it may be placed below the frame, or it may be used at any point between the top and bottom of the rod B. If this bridge is to be attached to the rods L and made vertically adjustable, two set-screws will have to be used for the purpose of adjusting the bridge up and down.

Having thus described my invention, I claim—

1. The combination of the tripod, the staff which is secured thereto, and which has a separate bearing-point attached to its upper end, with the table having a socket in its top to re-

ceive a pivot upon which the sighting-tube is placed, and a socket in its under side, and a counter-balance connected to it by means of suitable rods, substantially as shown.

2. The combination of the table having a socket or bearing in its under side, a circular socket in its top, with the frame upon which the sighting-tube and level are placed, and which frame has a circular grooved pivot which catches in the socket, and the set-screws which are passed through the side of the table, so as to catch in the groove on the side of the pivot, substantially as shown.

3. The combination of the table or frame upon which the sighting-tube and the level are placed, with a counter-weight which is connected to the table at a suitable distance below it, the staff upon which the table is supported, a bridge which is connected to the counter-weight, and set-screws which are passed through the bridge for securing the table in any desired position, substantially as described.

4. The combination, in a leveling-instrument, of a frame upon which the sighting-tube and level are placed, with the bridge and a counter-weight which is suspended from the table, and which is connected thereto by suitable rods, the counter-weight and bridge having a slot or slots through them for their adjustment upon the rods, substantially as specified.

In testimony whereof I affix my signature in presence of two witnesses.

THOMAS J. BARRON.
